(57) **CLAIM**

The ornamental design for a multifunctional therapeutic device, as shown and described.

DESCRIPTION

FIG. 1 is a perspective view of a multifunctional therapeutic device showing my new design;

FIG. 2 is a front view of a multifunctional therapeutic device;

FIG. 3 is a rear view of a multifunctional therapeutic device;

FIG. 4 is a left side view of a multifunctional therapeutic device;

FIG. 5 is a right side view of a multifunctional therapeutic device;

FIG. 6 is a bottom plan view of a multifunctional therapeutic device; and,

FIG. 7 is a top plan view of a multifunctional therapeutic device.
